UNITED STATES PATENT OFFICE.

ANDREW J. FLOWERS AND MALON I. FLOWERS, OF SPRINGFIELD, MISSOURI.

SIDING-BRACKET.

SPECIFICATION forming part of Letters Patent No. 295,376, dated March 18, 1884.

Application filed January 31, 1884. (No model.)

To all whom it may concern:

Be it known that we, ANDREW J. FLOWERS and MALON I. FLOWERS, citizens of the United States, residing at Springfield, in the county 5 of Greene and State of Missouri, have invented certain new and useful Improvements in Siding-Brackets, of which the following is a specification, reference being had therein to the accompanying drawings.

10 This invention relates to an improved device to be employed in applying siding to frame buildings and finishes the ends of the same; and it consists of a siding-hook which can be employed to support the siding-boards as they 15 are successively secured to the studding of the building, and a saw or other cutting-instrument and mechanism for operating the same, all combined and arranged as more fully hereinafter specified.

20 In the accompanying drawings, Figure 1 represents a side elevation of our improved device. Fig. 2 indicates a transverse section on the line *x x* of Fig. 1, and Fig. 3 represents an elevation of the side opposite that shown 25 in Fig. 1.

The letter A indicates the frame or body of the hook, which may be constructed of wood or metal, or of both. The said frame, near the lower end of the same, is provided with an inclined or beveled face, *a*, corresponding to the inclination of the siding-boards, so as to hold the board to be applied in proper position, as more fully hereinafter set forth. The said lower portion is provided with an adjustable slide, 30 B, which may be moved in a line parallel to the beveled face, and adjusted by means of a bolt or screw, C, passing through a slot in the slide. The slide is provided with a short blade, D, to catch under the lower edge of the siding-board last secured to the building, and the upper part of the frame A is provided with a sliding spike, which is to be driven into the studding above to secure the hook. The frame A is recessed longitudinally, as indicated by 35 the letter E, and across said recess extends a guide, F, for the purpose hereinafter set forth.

The letter G indicates a saw, which is secured to a reciprocating back, H, which is arranged to slide in a longitudinal groove, I, in a frame, 50 L, which works vertically in grooves M, and which has an extension, N, passing through a slot, P, in the frame A, and which is kept by

a spring, R, by which the frame is held in normal position. The head connects by means of a pitman, T, with a crank-pin on a wheel, U, 55 which is mounted upon a shaft, V, and turns in a recess, W, the shaft passing through the frame A, and is provided with a pinion, X, which intergears with a cog drive-wheel, Y, which turns on a stud, Z, secured to the frame 60 A, as indicated.

The device is employed as follows: The lower end of the frame is placed with its beveled face against the board last secured and the blade is fastened under the lower edge of the board. 65 The pin is driven in the studding above, and fastens the frame in position. Two of the hooks are employed, the board being supported between the guard and the building. After the board is secured, the hooks are removed, placed 70 upon the ends of the board, and the saw operated to cut off the end, the frame being held by the handle A' in the left hand, the drive-wheel operated by the right, while the saw is pressed to its work by the left thumb, which 75 bears against the extension above named.

Having thus described our invention, what we claim, and desire to secure by Letters Patent, is—

1. In a siding-bracket provided with a saw 80 and means for operating the same, the combination, with the frame having an inclined or beveled bearing-face and containing said saw, of the pin or spike for entering the studding of a building, and the adjustable slide provided 85 with an adjustable knife which is adapted to fit under the siding already on said building, the whole device operating substantially as and for the purpose set forth.

2. In a siding-bracket provided with a re- 90 ciprocating saw and actuating mechanism, the combination of the frame having an inclined or beveled bearing-surface, and carrying said saw and actuating mechanism, with the supporting-guide for holding the board while being sawed, all arranged to operate substantially 95 as described.

3. The combination, with the frame and the supporting-guide, of the reciprocating saw, the adjustable frame which carries said saw and 100 its spring and extension, and the gearing whereby the saw is reciprocated, substantially as specified.

4. In a siding-bracket, the combination,

with the frame having an inclined bearing-surface, of the pin or spike, the adjustable slide carrying an adjustable knife, the reciprocating saw with the adjusting and the geared driving mechanism, the supporting-guide, and the handle, all arranged to operate substantially as and for the purpose set forth.

In testimony whereof we affix our signatures in presence of two witnesses.
